(57) **CLAIM**

The ornamental design for an air chute bracket, as shown and described.

DESCRIPTION

FIG. 1 is a top perspective view of an air chute bracket showing our new design;

FIG. 2 is a front view thereof;

FIG. 3 is a rear view thereof;

FIG. 4 is a top view thereof;

FIG. 5 is a bottom view thereof; and,

FIG. 6 is a right view thereof, and a left view (not shown) is a mirror image of FIG. 6.

Surface shading in the FIGS. 1-6 is provided to show clearly the character and contour of all surfaces of any three-dimensional aspects of the design.

1 Claim, 3 Drawing Sheets*Fig. 1*
